[57] CLAIM

The ornamental design for a combined touch up hair pick with spray dispenser, as shown and described.

DESCRIPTION

FIG. 1 is a perspective view of a combined touch up hair pick with spray dispenser showing my new design;
FIG. 2 is a top plan view;
FIG. 3 is a bottom view;
FIG. 4 is a side elevational view, the side not shown being a mirror image of the side shown;
FIG. 5 is an end elevational view; and,
FIG. 6 is an end elevational view of the end opposite that shown in FIG. 5.
